FIG. 5

FIG. 4

FIG. 2

FIG. 1

INVENTOR
O. FIGHTMASTER

BY *Wright & Glenn*

ATTYS

UNITED STATES PATENT OFFICE.

OMER FIGHTMASTER, OF SAN FRANCISCO, CALIFORNIA.

AUTOMOBILE HEADLIGHT.

Application filed April 13, 1922. Serial No. 552,326.

To all whom it may concern:

Be it known that I, OMER FIGHTMASTER, a citizen of the United States, residing at San Francisco, in the county of San Francisco and State of California, have invented new and useful Improvements in Automobile Headlights, of which the following is a specification.

This invention relates to improvements in automobile headlights and its primary object is to provide a headlight of simple and inexpensive construction which will prevent the "blinding" of pedestrians and of the drivers of approaching automobiles and eliminate all objectionable and confusing "glare", without appreciably lessening the illuminating qualities of the headlight.

An object of the invention is to provide a novel form of reflector which may be readily incorporated with the ordinary lamp casing or housing and is of such construction that it will prevent the upward projection of light rays, the adaptability of the reflector being such that it will permit of the conversion of an ordinary headlight into a non-glaring and non-blinding headlight.

A further object is to provide a headlight of the character described in which provision is made for dim illumination, especially suitable as a parking light.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claim may be embodied in a plurality of forms.

Referring to the drawings:

Fig. 1 represents a front elevation of a headlight constructed in accordance with my invention.

Fig. 2 represents a vertical sectional view of the headlight.

Fig. 3 represents a side elevation of the reflector unit as when removed from the lamp housing or casing.

Fig. 4 is a diagrammatic view showing the manner in which the light rays are controlled by the reflector.

Referring to the embodiment of the inven-

tion illustrated in the accompanying drawings, 1 designates a shallow parabolical reflector having arranged at the focus thereof an incandescent lamp 2, after the manner well known in the art. Extending forwardly from the perimeter of the lower part of the reflector 1 and being either attached to, or integral with said reflector is a plate or shield 3, which is curved in cross section but longitudinally flared towards its outer end whereby it extends divergently with relation to the reflector. The shield 3 is attached to the lower part of a supporting annulus or ring 4, which latter is adapted to engage against an angle iron ring 5 mounted upon a lamp casing 6. A lens 7 of the usual form is mounted in the casing and held in place by an annular member 9 carried on the lamp housing.

Contiguous with the shield 3 as a separate piece or an integral part thereof and extending from the periphery of the upper part of the reflector 1, is a hood or shield 10 which is downwardly and outwardly inclined from the upper edge of the reflector and terminates at its forward end below the plane of the source of illumination so that the light 2 and the greater part of the reflector are invisible from a point in front of the lamp. The shield 10 is provided on its under side with a main reflecting surface 11 and side reflecting surfaces 12, which latter are outwardly divergent, in keeping with the shield 3. The inner side of the shield 3 is rendered non-reflecting by a covering of gray paint or any other suitable non-reflecting coating, as shown at A. Only the lower portion, (less than half) of the parabolic reflector is visible from a point in front of the lamp and as this portion is comparatively small it will not produce a glaring or blinding effect when looking directly into the lamp from a point ahead.

In my invention the shield conceals more than half of the main reflecting surface without materially detracting from the reflection produced thereby and by rendering the other visible portions of the reflecting unit non-reflecting, the headlight is thereby made glare proof. Thus, only a small reflecting surface will be visible when looking directly into the headlight from a point ahead, say, beyond about sixty feet, but when closer than this, the reflector is entirely hidden from view. It will thus be seen the essential structural features of the

invention are the hood or shield which, like a visor, extends downwardly and forwardly in front of more than half of the main reflecting surface, the reflecting surfaces on the inner surface of the hood which serve to intensify the reflection of light and cause downward and outward projection of the light rays and the non-reflecting surfaces beneath the hood.

- 10 As shown in the diagram in Fig. 4, of the drawing, the rays are projected forwardly instead of upwardly and forwardly. The parabolic reflector is of necessity, comparatively shallow but of such formation that when arranged in the relation shown in the drawing to the specially constructed hood 10 having reflecting surfaces 11 and 12, the light rays will be projected forwardly and downwardly instead of being upwardly projected.

15 The inclined hood or visor 10 provides a space B in which a small incandescent lamp 14 may be mounted. The upper portion of the lens is preferably painted green, as shown at C, in Fig. 1, so as to provide a dim illumination, particularly useful as a 20 parking light.

25 With reference to the foregoing description and accompanying drawings, it will be seen that this invention contemplates the provision of a headlight which when looking into the headlight from a point, for example up to about sixty feet ahead, no por-

tion of the reflecting surface will be visible yet adequate illumination is provided by the headlight. The ordinary vehicle headlight is substantially twenty-eight inches from the ground and assuming that the elevation of the driver of an approaching vehicle is substantially six feet, with the headlight of my invention, after the on-coming or approaching vehicle passes a point about sixty feet in front of the headlight, the formerly visible extremely small lower portion of the reflector is entirely hidden from view 45 and all glare whatever is eliminated.

40 I claim:

45 A headlight comprising a casing, a substantially vertically disposed parabolic reflector mounted within the casing, an electric light disposed at the focal plane of the reflector, an arcuate hood extending from the upper half of the reflector forwardly and downwardly with its lower edge disposed below the focal plane of the reflector, the 50 lower edge of said hood being substantially horizontal and extending entirely across said casing, said hood having a reflecting surface on its inner side and an arcuate shield extending forwardly from the lower half of the reflector and joined at its upper edges to said hood, which shield is provided on its inner side with a non-reflecting surface and is flared from its inner to its outer end.

55 60 65 OMER FIGHTMASTER.
